DESIGN FOR A FIRE EXTINGUISHER

Powell Evans, Haverford, Howard P. Jarden,
Philadelphia, and George W. Schmunk, Croydon, Pa., assignors to said Powell Evans

Application December 30, 1941, Serial No. 104,920

Term of patent 14 years

To all whom it may concern:

Be it known that we, Powell Evans, Howard P. Jarden, and George W. Schmunk, citizens of the United States, residing in Haverford, Montgomery County, Pa., Philadelphia, Philadelphia County, Pa., and Croydon, Bucks County, Pa., respectively, have invented a new, original, and ornamental Design for a Fire Extinguisher, of which the following is a specification, reference being had to the accompanying drawing, forming a part thereof, in which the figure is a side elevational view of a fire extinguisher showing our new design, the illustration being characteristic of the appearance of the extinguisher when viewed from any side. The dominant features of the design reside in the portions shown in full lines.

We claim:

The ornamental design for a fire extinguisher, substantially as shown and described.
